DESIGN FOR A CHRISTMAS TREE ORNAMENT

Lambert L. Raymond, Minneapolis, Minn.

Application March 26, 1934, Serial No. 51,174

Term of patent 14 years

To all whom it may concern:

Be it known that I, LAMBERT L. RAYMOND, a citizen of the United States, residing at 2638 Upton Avenue North, Minneapolis, in the county of Hennepin and State of Minnesota, have invented a new, original, and ornamental Design for a Christmas Tree Ornament, of which the following is a specification, reference being had to the accompanying drawing, forming part thereof.

The figure is a view in elevation of a Christmas tree ornament showing my new design. The shading represents any color.

I claim:—

The ornamental design for a Christmas tree ornament, as shown and described.

LAMBERT L. RAYMOND.
